[57] CLAIM

The ornamental design for a pour cup for filling containers, as shown and described.

DESCRIPTION

FIG. 1 is a perspective view of a pour cup for filling containers showing my new design;

FIG. 2 is a front elevational view thereof, whereby the back elevational view is a mirror image thereof;

FIG. 3 is a side elevational view thereof, whereby the opposing side is a mirror image thereof;

FIG. 4 is a top plan view thereof;

FIG. 5 is a bottom plan view thereof; and,

FIG. 6 is a bottom plan view thereof.

FIG. 1

FIG. 2

FIG. 3

FIG. 4

FIG. 5

FIG. 6
